Primary Examiner — Melanie H Tung*Assistant Examiner* — Darmawan Truong(74) *Attorney, Agent, or Firm* — Klarquist Sparkman, LLP(57) **CLAIM**

I claim the ornamental design for a display screen or portion thereof with graphical user interface, as shown and described.

DESCRIPTION

The FIGURE is a front view of a display screen or portion thereof with graphical user interface showing my new design.

The broken lines forming a perimeter in the drawing illustrate a display screen or a portion thereof and form no part of the claimed design. The remaining broken lines in the drawing illustrate portions of the graphical user interface that form no part of the claimed design.
